CLAIM

The ornamental design for an electronic article surveillance pedestal, as shown and described.

DESCRIPTION

FIG. 1 is a front, right perspective view of an electronic article surveillance pedestal embodying our new design;

FIG. 2 is a front, left perspective view thereof;

FIG. 3 is a right-side view thereof;

FIG. 4 is a left-side view thereof;

FIG. 5 is a front view thereof;

FIG. 6 is a back view thereof;

FIG. 7 is a top view thereof; and,

FIG. 8 is a bottom view thereof.

The broken lines show portions of the electronic article surveillance pedestal that form no part of the claimed design.

1 Claim, 6 Drawing Sheets
